UNITED STATES PATENT OFFICE.

RICHARD C. LEAKE, OF ROCHESTER, NEW YORK, ASSIGNOR TO GENERAL RAILWAY SIGNAL COMPANY, OF ROCHESTER, NEW YORK, A CORPORATION OF NEW YORK.

PROTECTIVE DEVICE.

1,380,300.

Specification of Letters Patent. Patented May 31, 1921.

Application filed July 8, 1919. Serial No. 309,278.

To all whom it may concern:

Be it known that I, RICHARD C. LEAKE, a citizen of the United States, and resident of the city of Rochester, in the county of Monroe and State of New York, have invented a new and useful Protective Device, of which the following is a specification.

This invention relates to protective devices for electric interlocking systems and particularly to devices which are sometimes termed cross-protection relays and are used to protect electric interlocking systems against improper operation of the parts or functions due to crosses between operating wires and similar derangements of the wiring and connections.

One object of my invention is to improve the design and construction of protective devices, by providing a device, which will be simple, reliable and efficient, comprise but few and rugged parts and which can be easily and cheaply manufactured.

Another object of my invention is to devise a protective device of the character described which will respond to the flow of alternating current through its coils but which will not be effected by direct current and one which after it has operated, the circuits which it may open cannot again be closed until the parts of the protective device are in such a position as to be immediately capable of reopening these circuits.

A further object of my invention is to devise a protective device which can be readily restored to its normal condition after it has been automatically operated, one which can be operated manually to facilitate inspection or repair, but which cannot be manipulated accidentally or intentionally in such a way as to interfere with or destroy the protection which it gives.

A still further object of my invention is to devise a protective device having all of the above-mentioned characteristics and one which after being operated automatically by an improper flow of current due to a cross, ground, or the like, cannot be restored to or improperly held in its normal condition to reestablish a path for said improper flow of current, until the cross or other condition causing said improper flow has ceased to exist.

Other objects and advantages will appear as the description of the invention progresses, and the novel features of the in-

vention will be particularly pointed out in the appended claims.

In describing the invention in detail, reference is made to the accompanying drawings, in which is illustrated a preferred physical embodiment of the invention, in which like reference characters designate corresponding parts in the several views, and in which:

Figure 1 is a vertical longitudinal section 65 of my protective device, some of the parts thereof being shown in full for the sake of clearness;

Fig. 2 is a vertical transverse section taken substantially on the line 2—2 in Fig. 70 1 viewed in the direction indicated by the arrows *a*;

Fig. 3 is a vertical transverse section taken substantially on the line 3—3 in Fig. 75 1 viewed in the direction indicated by the arrows *b*;

Fig. 4 is a fragmentary view showing the method of mounting the main shaft and the parts operatively connected thereto;

Fig. 5 is a fragmentary view showing the 80 method of operatively connecting the tripper arm with the contact fingers;

Fig. 6 is a diagrammatic view, partly in perspective with certain parts broken away and spread apart which shows in a simplified form the principal operating parts of the protective device; and

Fig. 7 is a view similar to Fig. 6 showing the parts in an operated position.

Referring to the accompanying drawings, 90 the protective device embodying my invention in general comprises a single element alternating current relay, specifically a relay of the vane type, together with associated contact devices adapted to be opened upon energization of the relay, and manually controlled operating and restoring devices for permitting the contacts to be opened or closed manually when desired. The protective device as illustrated is formed with a 95 box-like frame comprising a metallic casting having a base portion *B* with two upright end portions *R* and *F*, and a top block *T* of insulating material which is fastened to said end portions by screws 1. One of the 100 end portions *R* is provided with a bolt 2 by means of which the entire circuit controller is secured to a suitable supporting panel.

The end portion *R* is formed with two 110 parallel sides 3 extending a part of the way

along either side of the base B and connected at one end by an integral cross member 4, in which the bolt 2 is secured, see Fig. 1. Secured to the open ends of the 5 sides 3 by means of bolts 5 is a stacking of laminations constituting a core 6 of a general rectangular shape. Referring to Fig. 2, the bottom portion of the core 6 is formed with two poles 6^a—6^b, each of which 10 carries a coil 7 and a shade ring 8 in the same way and for the same purpose commonly employed in the construction of vane type relays. The coils 7 are held in a proper position on their respective poles by two resilient 15 spreaders 9 which are arranged between the coils 7 as shown in Figs. 1 and 2, and are adapted to resiliently urge the coils apart and hold them firmly against the outer portions of the core 6. These spreaders 9 are 20 made with their ends cut out to permit them to fit over the poles 6^a—6^b of the core 6 and are long enough to permit the end of one to overlap the end of the other.

The end portion F is similar in construction to the end portion R, being also formed with two parallel sides 10 connected at one end by an integral cross bar 11, see Figs. 1 and 3. Pressed into holes in bosses formed on the inside of each of said sides 10 are 25 bearings 12 which are secured therein by set screws 13, as shown in Fig. 4. These bearings 12 form supports for the ends of a transverse main operating shaft 14 which is mounted eccentrically therein, as shown 30 in Figs. 3, 4 and 6. Pinned to the shaft near one side (see Fig. 3) is a collar 15 having a circular flange or rim to which is riveted or otherwise suitably fastened a vane 16, best shown in Figs. 1 and 6. This vane 16 35 is formed with an elongated arm 16^a provided with a raised rib for strengthening purposes and having at its free end an enlarged vane portion 16^b. Another arm 16^c extending to the right from the bearing portion of said vane as viewed in Fig. 1 is formed at its outer end with a flange 16^d which is bent at right angles to said arm (see Fig. 6) for a purpose hereinafter explained.

40 The main shaft 14 is cut away near its middle to form a second eccentric bearing 17, said bearing being arranged on the side of the axis of said shaft 14 which is opposite to that on which the journal bearings for 45 said shaft are formed. This second eccentric bearing 17 forms a support for the bifurcated end 18 of a tripper arm TA which at its other end is pressed on a hub 19 carried on a cross member 20 of insulating 50 material (see Fig. 5). This cross member 20 is supported at each end in brackets 21 which are riveted to resilient contact fingers 22. The contact fingers 22 are arranged vertically being doubled over or looped at their 55 lower ends and fastened to rigid supports

23 secured to the top block T by binding posts 24. The contact fingers 22 are biased by an inherent tension to one position and are adapted to be moved against said bias and to make electrical contact in one extreme position of the device with angle shaped contact pieces 25 which are fastened to the underside of the top block T by bolts 26 or other suitable fastening means. Said angle shaped contact pieces 25 are preferably 70 formed with slots (not shown) through which the bolts 26 pass so as to facilitate adjustment of the contact pressure by adjusting said angle shaped pieces 25 rather than by bending the contact fingers 22. As 75 illustrated in Fig. 1, the contact fingers 22 are provided with back contact pieces 27 which are adapted to make electrical contact in the other extreme position of the protective device with a contact piece 28 80 preferably secured in a slot in the head of a bolt forming part of an additional binding post 29 mounted in the top block T. These contact pieces 27, however, are not a part of the usual construction of the device but may 85 be used if desired.

The tripper arm TA is provided with a notch or latch 30 which is formed on the underside of said arm near its right hand end (see Figs. 1 and 6), said latch 30 being 90 adapted to coöperate with a catch 31 secured to an upwardly extending lug 32 integral with a restoring handle H, for a purpose hereinafter more fully explained. This restoring handle H is formed with a hub or boss 33 on one side which is mounted on and secured by means of a cotter pin 34 to a pivot pin 35 located below the main shaft 14 and supported and journaled in the sides 10 of the end portion F so as to turn about 95 a horizontal axis. Extending to the left from the hub 33 of the handle H, as viewed in Fig. 1, and integral therewith is a bifurcated jaw 36 which is adapted to coöperate with a horizontal stop pin 37 for limiting 100 the movement of said handle H in either direction, said stop pin 37 being located to the left of said pivot pin 35 and parallel therewith and supported at its ends in the sides 10 of the end portion F. A spring 38 105 coiled around said pivot pin 35 and anchored at one end in the handle H and at its other end in the base B causes said handle H to be biased in one position against the stop pin 37. When the catch 31 is in 110 position in front of said latch 30 on said tripper arm TA, the biasing force of the handle H exerts a pressure on the contact fingers 22 thus holding said fingers firmly 115 against their respective contact pieces 25.

120 Stops are provided for limiting the movement of the vane in either direction. One of said stops designated 39 on the drawing is formed by a bent-up portion on the underside of the elongated arm 16^a of the vane 130

16 itself and is adapted to strike the upper edge of the tripper arm TA, thus limiting the downward movement of said vane 16. The other stop 40 consists of a metallic piece 5 bent at an angle, one leg of which being secured by rivets to the cross member 4 of the end portion R (see Fig. 1), and the other extending toward the right in the path of movement of said vane 16, thus being in a 10 position to limit the upward movement of said vane 16.

Resting on the upper face of the flange 16^a on the arm 16^c of the vane 16 is the enlarged head of an up-and-down plunger 15 rod 41 which is loosely guided in a hole in the cross bar 11 of the end portion F and also in a similar hole in the top block T. Said plunger rod 41 provides a means for testing the device by hand, as hereinafter 20 explained, or if desired an indicating means (not shown) may be attached thereto for indicating the operated condition of the device.

In order to prevent unauthorized tampering with my protective device, the operating parts thereof are preferably inclosed. The construction of the main skeleton or framework of the device incloses the operating parts on the top and bottom, and one 30 end, but leaves the other end and the two sides open. These portions are provided with a cover 42 having a general U-shape, which is slid in rabbets formed in the top block T and the base portion B, see Figs. 35 1, 2 and 3. This cover 42 is preferably made of thin sheet metal and its sides are normally sprung slightly inward so that when the cover is in position the sides being 40 slightly under tension, tend to hug close to the sides of the frame and hold the cover in position. There is also a lug 43 integral with the cross bar 11 on the end portion F, which is adapted to pass through a slot in the end of said cover 42; and by passing a 45 wire 44 through a transverse hole in the outer end of said lug and having its ends sealed, unauthorized removal of the cover is prevented.

Operation: The protective device embodying my invention is designed primarily to be used in connection with electric interlocking systems for railways which are operable with alternating current, for detecting improper application of alternating current to the control wires of said systems, such as may be produced by crosses, grounds, or the like. For this purpose the device should operate on alternating current and not on direct current. The occurrence of 55 said crosses have a tendency to cause an improper operation of the switch and place it out of correspondence with its control lever.

From the foregoing, it is apparent that unless means are provided for protecting 60 said systems against such improper opera-

tion of the switch, dangerous results may occur; and one important function performed by my protective device is to prevent false and improper operation of the switch under such conditions as described. 70

Referring more particularly to the operation of my protective device as herein described, the parts of this device are shown in their normal position in Figs. 1, 2, 3 and 6, and in an operated position in Fig. 7. 75 Normally the vane 16 is in its lower position due to its weight and the contacts 22-25 are held closed for the reason that the catch 31 on the restoring handle H is behind the latch 30 on the tripper arm TA, thereby forcing said arm over and consequently holding said contact 22-25 closed. 80

When alternating current flows through the coils 7 of the relay, the vane 16 is attracted upward in accordance with the principles governing the operation of the well known vane type relay. The upward movement of said vane 16 causes the main shaft 14 to be turned on its axis in a clockwise direction. The eccentric mounting of the 90 main shaft 14 together with the additional eccentric bearing 17 for the tripper arm TA causes said arm to be gradually lifted, as the main shaft 14 is turned in the direction stated, until the latch 30 on said tripper arm 95 is lifted free of the catch 31 on the restoring handle H, thus removing the pressure exerted on said tripper arm TA and permitting the contact fingers 22 due to their bias to trip open and thus interrupt any circuit 100 that might be taken through said contact fingers.

Referring to Fig. 7, it will be noted that when the above described tripping action has occurred, the underside of the tripper arm TA rests on the top of the catch 31 on the restoring handle H, thus holding the vane 16 up and preventing the main shaft 14 from returning to its original position even though current may have ceased to flow through the coils 7 of the relay. It will, therefore, be evident that the contact fingers 22 will not be again closed until restored by the operator. To restore the protective device to its normal condition and 115 again close the contacts 22-25, the operator presses down on the restoring handle H, thus moving the catch 31 on said handle from in under the tripper arm TA to a position behind the latch 30 on said tripper arm. This releases the tripper arm and permits the main shaft 14, which is biased by the weight of the vane 16, to return to its 120 normal position. So long as the handle H is held down, however, the contacts 22-25 stay open. When the operator releases the handle H, the coil spring 38 associated therewith forces said handle H about its axis in a counter-clockwise direction to its normal 125 position, and during this movement of the 130

handle H the catch 31 thereon engages with the latch 30 on said tripper arm TA and forces said arm toward the left as viewed in Fig. 7, thus causing the contacts 22-25 to be again closed and a pressure exerted on the contact fingers 22.

In case the cross, ground, or the like, which previously caused the flow of alternating current through the coils 7 of the 10 protective device, still exists when the parts are restored, the vane 16 is immediately moved upward, and the same movement and operation of the parts hereinbefore described is produced to cause immediate opening of the contacts 22-25. It should be noted that the operator cannot prevent this second operation, because any attempt on his part to manipulate the restoring handle H to keep the contacts 22-25 closed is of no 20 avail. The same operations will be repeated so long as the cross grounds or the like exists and so long as the operator attempts to restore the protective device.

From the foregoing, it can be seen that 25 after the protective device has operated, the circuits which it may open cannot again be closed until the parts of the protective device are in such a position as to be immediately capable of reopening these circuits. 30 The operator consequently, cannot carelessly or maliciously restore the protective device while the cross, ground, or the like exists, nor can he maliciously prevent the proper operation of the protective device or detract 35 from its efficiency by manipulation or by fastening down the handle H.

The up-and-down plunger rod 41 provides a means for permitting the operator to test the device by hand to determine whether or 40 not it is in good working condition, or to hold the contacts 22-25 open for any other reason. When this plunger 41 is pressed down by the operator, the lower end of which rests normally on the flange 16^a on 45 the arm 16^c of the vane 16, the shaft 14 is caused to turn in the same way as if alternating current were to flow through the coils, thus lifting the tripper arm TA until the latch 30 is disengaged and permitting 50 the contacts 22-25 to trip open, in which position they are held as previously explained until restored by the operator, which he may do by operating the restoring handle H in the same way as hereinbefore described.

Various modifications and changes may be made in the particular form of construction and arrangement of parts of the protective device shown and described without materially changing the functions and advantages of the device and without departing from my invention. For example, the back contact piece 27 may be added to the contact fingers, as shown in Fig. 1 and described 65 hereinbefore. It will be evident that with

this additional contact, circuits may be controlled when the protective device is in either of its extreme positions.

While the protective device herein disclosed has been described in connection with 70 electric interlocking systems and while I have shown and described one physical embodiment of my invention, I desire to have it understood that the particular embodiment and application thereof selected is merely 75 illustrative and does not exhaust the possible physical embodiments of means underlying my invention.

What I claim as new and desire to secure by Letters Patent of the United States, is: 80

1. A protective device for safeguarding electric interlocking systems comprising a normally closed circuit controller biased to open position, means including a co-operating latch and catch and operatively connected to said circuit controller for holding it in its normal position, and an electro-magnetic device including a vane adapted to trip said latch to permit said circuit controller to open when alternating current is 90 supplied to the electro-magnetic device. 85

2. A protective device for safeguarding electric interlocking systems comprising a normally closed circuit controller biased to open position, means including a co-operating latch and catch and operatively connected to said circuit controller for holding it in its normal position, electro-magnetic means including a vane for disengaging said latch and catch to permit said circuit controller to open, and manually operable means for reengaging said catch and latch, said manually operable means while in its restoring position acting to permit said circuit controller to remain open. 100 95

3. A protective device for safeguarding electric interlocking systems comprising a normally closed circuit controller biased to open position, electro-magnetic means including a vane and adapted to be moved to an operated position by alternating current through said means, means including a co-operating latch and catch for holding said circuit controller in its normal position, said vane acting upon movement to an operated position to trip said latch and permit said circuit controller to open, said catch acting after said latch is tripped to hold said vane in its operated position, and manually operable means for restoring said circuit controller to its closed position. 110 115

4. A protective device for safeguarding electric interlocking systems comprising a circuit controller biased to open position, means for normally holding said circuit controller latched against its bias in a closed position, electro-magnetic means including a movable member adapted upon movement to an operated position to actuate said means and unlatch said circuit controller to 120 125 130

- permit it to open, and manually operable means for restoring said movable member and circuit controller to the normal position.
5. A protective device for safeguarding electric interlocking systems comprising a normally closed circuit controller biased to open position, means including a latch operatively connected to the circuit controller, 50 a manually operable restoring member provided with a catch adapted to engage said latch, a spring associated with the restoring member and acting to actuate said circuit controller against its bias to a closed position, and electro-magnetic means including a pair of operating coils and a vane actuated upon energization of said coils for automatically disengaging said latch and catch to permit said circuit controller to open, 55 said catch acting after the disengagement of said latch and catch to hold said vane in an operated position.
6. A protective device for safeguarding electric interlocking systems comprising a normally closed circuit controller biased to open position, means including a latch operatively connected to the circuit controller, a manually operable restoring member provided with a catch adapted to coöperate 60 with said latch, a spring acting upon said restoring member adapted to hold the circuit controller closed while the latch and catch are engaged, and electro-magnetic means for automatically disengaging said latch and catch.
7. A protective device for safeguarding electric interlocking systems comprising a circuit controller having a resilient contact finger biased to an open position, a tripper arm pivotally secured at one end to said contact finger and provided at its other end with a latch, a manually operable restoring member provided with a catch adapted to engage said latch, a spring associated with 65 the restoring member and acting to force said contact finger against its bias to a closed position, and electro-magnetic means for automatically tripping said latch to permit said contact finger to open.
8. A protective device for safeguarding electric interlocking systems comprising a normally closed circuit controller biased to open position, a tripper arm operatively connected at one end to said circuit controller and provided with a bifurcated jaw having a slot therein, said arm also being provided with a latch, a shaft mounted to turn in either direction and provided with a guiding member arranged eccentric to the 70 axis of said shaft, said member being adapted to rest in the slot in said jaw and to guide one end of said tripper arm, a manually operable restoring means provided with a catch adapted to engage said latch, a spring associated with the restoring means 75 and acting to force said circuit controller against its bias to a closed position, and electro-magnetic means including a vane directly connected to said shaft and adapted upon movement to an operated position to turn said shaft and automatically disengage said latch and catch to permit said circuit controller to open.
9. A protective device for safeguarding electric interlocking systems comprising a normally closed circuit controller biased to open position, a tripper arm operatively connected at one end to said circuit controller and provided with a bifurcated jaw having a slot therein, said arm also being provided with a latch, a shaft mounted to turn in either direction and provided with a guiding member arranged eccentric to the 80 axis of said shaft, said member being adapted to rest in the slot in said jaw and to guide one end of said tripper arm, a manually operable restoring means provided with a catch adapted to engage said latch, a spring associated with the restoring means 85 and acting to force said circuit controller against its bias to a closed position, electro-magnetic means provided with a pair of coils and a vane directly connected to said shaft and adapted upon energization of said coils to be moved to an operated position 90 whereby said shaft is turned and automatically disengages said latch and catch permitting the circuit controller to open, and other means for manually moving said vane to an operated position to permit said circuit controller to open.
10. A protective device for safeguarding electric interlocking systems comprising a normally closed circuit controller including a resilient contact finger, an electro-magnetic device including a pair of coils and a movable member said member being secured to a shaft and adapted to turn therewith, means guided by said shaft and constituting an operative connection between said movable member 95 and said contact finger to resiliently hold said contact finger in a closed position, and means actuated by the movement of said movable member to an operated position to break said holding connection and permit 100 said contact finger to move to an open position.
11. A protective device for safeguarding electric interlocking systems comprising a normally closed circuit controller including a resilient contact finger biased to open position, an electro-magnetic device including a movable member secured to and adapted to turn said shaft upon movement to an 105 operated position, an eccentric formed with said shaft, a tripper arm guided at one end by said eccentric and operatively connected to and insulated from said contact finger at its other end, and a latch on said tripper arm adapted to engage with a catch on a manu- 110
12. A protective device for safeguarding electric interlocking systems comprising a normally closed circuit controller including a resilient contact finger biased to open position, an electro-magnetic device including a movable member secured to and adapted to turn said shaft upon movement to an 115 operated position, an eccentric formed with said shaft, a tripper arm guided at one end by said eccentric and operatively connected to and insulated from said contact finger at its other end, and a latch on said tripper arm adapted to engage with a catch on a manu- 120
13. A protective device for safeguarding electric interlocking systems comprising a normally closed circuit controller including a resilient contact finger biased to open position, an electro-magnetic device including a movable member secured to and adapted to turn said shaft upon movement to an 125 operated position, an eccentric formed with said shaft, a tripper arm guided at one end by said eccentric and operatively connected to and insulated from said contact finger at its other end, and a latch on said tripper arm adapted to engage with a catch on a manu- 130

ally operable restoring means, said restoring means being provided with a spring adapted to force said contact finger against its bias to a closed position, said latch and catch 5 being disengaged by said eccentric when said shaft is turned in one direction.

12. A protective device for safeguarding electric interlocking systems comprising a circuit controller having a pair of resilient 0 contact fingers adapted to make electrical contact in either of two extreme positions and being biased to one of said positions, a shaft mounted to be turned in either direction and including an eccentric, a tripper

arm guided by said eccentric and operatively 15 connected to said contact fingers, resilient means acting upon said tripper arm to urge said contact fingers to one extreme position against said bias, and electro-magnetic means including a movable member secured to and 20 adapted to turn said shaft when said member is moved to an operated position, whereby said tripper arm is automatically released to permit said contact fingers to trip open in one extreme position and to close 25 in the other of said extreme positions.

RICHARD C. LEAKE.
